US0D1066756S

(12) **United States Design Patent** (10) **Patent No.:** **US D1,066,756 S**
(45) **Date of Patent:** **** Mar. 11, 2025**

(54) **BRICK FORMLINER**

(71) Applicant: **Architectural Polymers, Inc.**,
Palmerton, PA (US)

(72) Inventor: **Marshall Gilbert Walters**, Lehighton,
PA (US)

(73) Assignee: **Architectural Polymers LLC**,
Palmerton, PA (US)

(**) Term: **15 Years**

(21) Appl. No.: **29/848,702**

(22) Filed: **Aug. 4, 2022**

(51) LOC (15) Cl. **25-99**

(52) U.S. Cl.

USPC **D25/199**

(58) **Field of Classification Search**

USPC D25/199, 138, 48.8, 164, 119;

D15/135-136; D7/672, 675, 677

CPC E04G 9/10; B28B 7/0073; E04B 1/2403;

E04B 1/19; E04B 1/2608

(57) **CLAIM**

The ornamental design for a brick formliner, as shown and described.

DESCRIPTION

FIG. 1 is a top-front-right side perspective view of a brick formliner, showing the design;

FIG. 2 is an enlarged view of the top-right corner of the view of FIG. 1, showing the design;

FIG. 3 is a bottom-rear-left view of the brick formliner of FIG. 1, showing the design;

FIG. 4 is an enlarged view of the bottom-left corner of the view of FIG. 3, showing the design;

FIG. 5 is a front elevation view of the brick formliner of FIG. 1, showing the design;

FIG. 6 is a rear elevation view of the brick formliner of FIG. 1, showing the design;

FIG. 7 is a right side elevation view of the brick formliner of FIG. 1, showing the design;

FIG. 8 is a left side elevation view of the brick formliner of FIG. 1, showing the design;

FIG. 9 is a top plan view of the brick formliner of FIG. 1, showing the design; and,

FIG. 10 is a bottom plan view of the brick formliner of FIG. 1, showing the design.

The broken-line boundaries in FIGS. 1 and 3 define the enlarged views shown in FIGS. 2 and 4 and these broken-line boundaries in FIGS. 1-4 form no part of the claimed design.

1 Claim, 8 Drawing Sheets
